[57] CLAIM

The ornamental design for a table lamp, as shown and described.

DESCRIPTION

FIG. 1 is a side elevational view of a table lamp showing my new design, the opposite side being a mirror image; FIG. 2 is a side elevational view thereof with the diffuser in an alternate position;

FIG. 3 is a front elevational view thereof with the diffuser in the position shown in FIG. 1, the rear being a mirror image;

FIG. 4 is a top plan view thereof;

FIG. 5 is a bottom plan view thereof;

FIG. 6 is a side perspective view thereof on a slightly reduced scale, the diffuser being in the position shown in FIG. 2.

The slots shown in the diffusers are partially shown in FIGS. 2, 5, and 6 for convenience of illustration.
